United States Patent

Des. 237,950

Patented Dec. 9, 1975

237,950

DRAFTING INSTRUMENT

Peter S. Hoagland, 18769 Saratoga, Lathrup Village,
Mich. 48076

Original design application Dec. 15, 1971, Ser. No. 208,511, now Patent No. D. 232,051, which is a continuation in part of Ser. No. 160,234, dated July 6, 1971, Patent No. D. 226,226. Divided and this application Jan. 2, 1974, Ser. No. 429,790

Term of patent 14 years

Int. Cl. D10—04

U.S. Cl. D10—62

FIG. 1.

FIG. 2.

FIG. 1 is a top left perspective view of a drafting instrument showing my new design, the bottom being generally plain; and

FIG. 2 is a right side elevational view thereof.

This is a divisional application of Ser. No. 208,511, filed Dec. 15, 1971, now Pat. No. D. 232,051, which is in turn a continuation-in-part of Ser. No. 160,234, filed July 6, 1971, now Pat. No. D. 226,226.

I claim:

The ornamental design for a drafting instrument, as shown and described.
